Primary Examiner — Ryan Harvey

(57) **CLAIM**

The ornamental design for a skipping rope handle, as shown and described.

DESCRIPTION

FIG. 1 is a front perspective view of a skipping rope handle according to the present invention;

FIG. 2 is a front elevation view thereof;

FIG. 3 is a rear elevation view thereof;

FIG. 4 is a left side view thereof;

FIG. 5 is a right side view thereof;

FIG. 6 is an enlarged top side view thereof; and,

FIG. 7 is an enlarged bottom side view thereof.

The broken lines in the drawings are for the purpose of illustrating portions of the skipping rope handle that form no part of the claimed design.
